STOCKING

Edwin Brand Beacham, Easton, Pa.

Application April 24, 1940, Serial No. 331,284

3 Claims. (Cl. 66—172)

This invention relates to stockings; and it has reference more especially to stockings with zones or bands near their tops capable of lengthwise stretching incident to knee bending, thereby to absorb strains such as would be likely to cause ruptures or runs in the stocking legs.

The formation of the strain absorbing zones in stockings of the kind referred to involves the use of covered elastic yarn which is much heavier (thicker) than the inelastic yarn employed in the knitting of the other portions of the stockings. This characteristic is particularly true of covered elastic yarn manufactured under U. S. Patent #2,024,156 granted to B. H. Foster on December 13, 1935 having a twisted core and two separate ply coverings wound in the direction opposite to that of the core twist. Strain absorbing zones or bands plain knitted from such yarn are bulky and have a tendency to curl, and so detract from the appearance and salability of the stockings, and moreover, by reason of the aggregate strength of the compacted rubber do not yield sufficiently for the intended purpose. The foregoing is true even though the zones or bands are loosely knitted.

The aim of my invention is to make it possible to incorporate covered elastic yarns, particularly of the patented kind supra, in stockings, and at the same time eliminate the above objectionable features. This desideratum I realize in practice as more fully disclosed hereinafter, by forming, incident to the knitting of the strain absorbing zones or bands, single courses from the covered elastic yarn in which every other loop is transferred laterally to the adjacent wale, in alternation with plain courses made from inelastic yarn of substantially the same gauge or count as that used in the body of the stocking, preferably synthetic yarn manufactured under U. S. Patent #2,130,948 granted to Wallace Hume Carothers on September 20, 1938. Strain absorbing zones or bands so produced will not only lie perfectly flat when relaxed and have the proper characteristics as regards yielding capacity, but will compare more favorably to the sheer texture of the other parts of the stockings, and, instead of marring the appearance of the hosiery, will actually add to its attractiveness.

In the drawing, Fig. 1 is a view, in side elevation, of a stocking conveniently embodying my invention.

Fig. 2 is a fragmentary view drawn to a larger scale, showing the texture of the stocking fabric; and

Fig. 3 is a fragmentary view of the kind of 55 compare more nearly to the sheer ness of the

covered elastic yarn employed in the formation of the strain absorbing zone or band of my improved stocking.

As depicted in Fig. 1, the stocking has a leg portion 5 which is plain knitted from fine gauge synthetic yarn of the kind referred to hereinbefore, although it may be of silk, rayon or other material; a "welt" or garter-attaching top portion 6 (which may be either of single or double thickness fabric) likewise plain knitted from the inelastic yarn; and an intermediate strain absorbing zone or band 7 in which the elastic yarn is incorporated as will be explained presently, so as to be capable of yielding both lengthwise and circumferentially of the stocking. The kind of elastic yarn which I prefer to employ is illustrated in Fig. 3 and generally designated by the letter E, having a core R of rubber twisted in one direction, an intermediate covering C of textile fibers wound in the opposite direction, and an outer thread layer L twisted in the same direction as said intermediate covering.

From Fig. 2, it will be observed that the zone or band 7 is formed with single loose courses 8 of the covered elastic yarn E (which is conventionally represented in heavy lines), in which the loop 9 of every other wale is laterally transferred and doubled with the loop 10 of the next adjacent wale. It will also be noted from Fig. 2 that 25 corresponding picot stitches resulting from such transferring in the several courses 8 are not at true vertical alignment, that is to say, they are on a slight bias relative to the direction of the fabric wales. Alternating with the courses 8 are 30 plain courses 11 and 12 of the inelastic yarn which is designated by the letter Y and which may be, and preferably is, of the same material and gauge as the yarn Y' employed in the leg and top portions 5 and 6 of the stocking. Also 35 by preference, the loops 13 in the courses 11 are made relatively large as compared with the loops 14 in the courses 12 which latter loops may correspond in size to those in the other portions of the stocking. As a consequence of this construction, the strain absorbing zone or band 7 is given just the proper capacity for expanding or stretching lengthwise of the stocking to the desired or necessary degree, and, when relaxed, assumes a condition of perfect flatness with the rest of the 40 stocking. Furthermore, by forming the loose open single courses 8 of the elastic yarn E directly next to the relatively loose courses 11 of the thinner inelastic yarn Y, the aspect of coarseness in the band is avoided and its texture made to 45

stocking body. The strain absorbing zone is therefore not objectionably conspicuous, and in fact, enhances rather than detracts from the appearance and salability of the stocking.

My invention is of course not to be considered as limited to the precise details of construction herein shown and described by way of example, since various modifications thereof are possible within the scope of the appended claims.

Having thus described my invention, I claim:

1. A stocking comprising a leg portion; a garter-attaching portion at the top; and a strain-absorbing zone between said leg and said garter-attaching portion, in which zone plain loop courses of inelastic yarn alternate with courses

15 of elastic yarn having enlarged loops in spaced wales transferred laterally all in the same direction and doubled in each instance with the loop in the next adjacent wale.

5 2. A stocking according to claim 1 in which the loops of the plain courses of inelastic yarn immediately adjacent the course of the elastic yarn in the strain-absorbing zone are also enlarged.

10 3. A stocking according to claim 1 wherein corresponding stitches formed by the laterally transferred loops in the several elastic courses are on a bias relative to the direction of the fabric wales.

EDWIN BRAND BEACHAM.
